UNITED STATES PATENT OFFICE.

FRED J. MARTIN, OF OAKLAND, CALIFORNIA.

CRYSTAL DETECTOR.

Application filed January 21, 1925. Serial No. 3,854.

This invention relates broadly to radio apparatus and specifically to detectors of the crystal type.

I have found from practice that contact between the selected sensitive spot of a crystal and its coating electrode, commonly called "cat's whisker", can be definitely maintained or preserved against the action of extraneous vibrations by yieldingly holding the electrode or cat's whisker against lateral movement at a point to one side of the crystal. By this newly discovered means, no interruption is caused in a radio circuit through temporary dislocation of the electrode from its crystal as was the case in this type of instrument as heretofore devised and known.

My invention is characterized by a crystal holder and means for associating an electrode with respect to the crystal so as to hold the former and the latter against relative movements when a selected spot on the crystal is found.

More specifically, my invention is characterized by a crystal holder which can be moved universally with respect to its coating electrode so that a very large range of selectivity can be had, and means for holding the electrode against shifting in a lateral direction after desired adjustment thereof has been obtained.

With the above and other objects in view which will appear as the nature of the invention is better understood, the same consists in the improved construction and novel arrangements of parts which will hereinafter be fully described and particularly pointed out in the claims.

In the accompanying drawings has been illustrated a single and preferred form of the invention, it being, however, understood that no limitations are necessarily made to the precise structural details therein exhibited, but that changes, alterations and modifications within the scope of the claims may be resorted to when desired.

Figure 1 is a vertical longitudinal section through the detector;

Figure 2 is a section taken on line II-II of Figure 1;

Figure 3 is an end view of the yieldable body; and

Figure 4 is a section on line IV-IV of Figure 1.

In carrying the invention into practice, use is preferably made of a barrel 5 which

may be formed of insulating material. At one end the barrel is formed with a head 6 having a relatively large central opening 7. The opposite end of the barrel is exteriorly threaded at 8 to accommodate the correspondingly internally threaded flange 9 of a cap 10. This cap is formed of metal, and same is provided with an integral extension 11 having a central threaded bore 12, and an external thread 13, the free end of the extension being split radially at 14 so that portions of the extension can be adjusted with respect to the axis of the bore 12.

The barrel may be mounted upon an insulating panel 15, or otherwise suitably supported when arranged in circuit with a radio instrument. In this respect I do not wish to limit myself, as this forms no particular part of my invention.

Within the barrel at a point adjacent to the head 6 is a crystal holder 16 carrying any suitable well known form of crystal 17 exposed as shown in order that it may be brought into active contact with the electrode, which I will describe presently. This crystal holder carries a screw 18 which extends through the large opening 7 so that it may be moved laterally and in fact universally with respect to the walls of said opening. In this manner, the position of the holder 16 may be changed with respect to the center of the barrel. Any desired adjustment of the crystal holder can be obtained by means of the clamp nuts 19 and 20 which are mounted on the screw 18. This screw acts in the capacity of a binding post and connected with the screw and with the nuts 19 and 20 is a metal clip or plate 21 which may be arranged in an electric circuit.

Within the barrel at a point between the crystal 17 and the head 10 is a cylindrical elastic or yieldable body 22, preferably, but not necessarily, formed of cork, the latter being found very desirable for the purpose intended. The external diameter of the body 22 is substantially co-extensive with the internal diameter of the barrel 5 to the extent that the body 22 may be moved axially of the barrel and against or toward the crystal.

A follower plate 23 is mounted behind the body 22 at one side of the cap 10 so as to be advanced against the body on the application of pressure to the plate. Movable in the bore 12 of the extension 11 is a feed screw 24 having its free end formed with a

nurled manipulating knob 25. The opposite end of the screw has a reduced threaded portion 26 extended into a correspondingly threaded aperture in the follower plate 23.

5 Said extension 26 carries an electrode 27 which in the present instance consists of a single length of wire normally about co-extensive, or less in length than the body 22.

The extension 12 of the cap 10 forms a 10 binding post for the second terminal of the circuit in which the crystal is mounted, and in view thereof the extension is provided with clamping nuts 28 and 29 between which a wire receiving clip 30 is clamped. The 15 extension also carries a clamping nut 31 which embraces the split portions of the extension 12 so that same can be advanced into locking contact with the screw 24 to hold the latter in a relatively fixed position of 20 longitudinal adjustment.

Having described the details of construction of my improved crystal detector, their operation is advanced as follows:

A desired position of the crystal is first 25 obtained within the barrel and the electrode 27 is brought into its selected position with the spot desired. As previously stated, the electrode or cat's whisker is substantially co-extensive with, or less in length than, the body 22, and consequently it does not protrude therefrom. When the follower plate 23 is advanced toward the head 6 under the action of the screw 24, the body 22 is gradually advanced toward the crystal. As this 30 body tends to compress, it follows that the effective contact end of the electrode or cat's whisker, being normally shorter than the body 22, naturally tends to protrude from the adjacent face of the body at the crystal 35 so that it finds active circuit contact with the selected spot on the crystal. Also at this time the annular surface of the body 22 is hugged or snugly embraced by the walls of the barrel 5.

40 Incident thereto, the electrode or cat's whisker 27 is guarded against accidental displacement from the crystal through the action of extraneous vibrations. In crystal detectors of the type heretofore known the 45 electrode or cat's whisker is extremely delicate, and one shaking the same accidentally or through the act of walking over a floor or jarring the radio instrument would cause dislocation of the electrode with respect to the crystal, and immediately the instrument 50 is thrown out of circuit and it becomes necessary for the operator to select another sensi-

tive spot in order that the set will properly function. I am able to eliminate this objection, and by the means employed herein 60 secure a position of relative permanency of the electrode or cat's whisker with respect to the selected spot on the crystal; and once an adjustment is had or a selected spot found, ordinary vibration will not in any 65 way affect the circuit of the set.

As previously stated, I am broadly interested in the provision of means capable of being associated with the electrode or cat's whisker of a crystal detector so as to hold same against vibration laterally and maintain its position in effective contact with its coacting crystal. In view thereof, I do not wish to be limited to the precise details of construction herein employed nor to the materials used. I refer to cork as being very desirable when constructing a body 22 that will yield and function satisfactorily as herein set forth. Any well-known composition of matter which will enable the electrode or cat's whisker to be protruded from a surface thereof and operatively positioned with respect to the crystal will or might suffice for my purpose.

55 Lateral displacement of the electrode is guarded against the means herein set forth and just described. Longitudinal displacement is guarded against by means of the nut 31 functioning through the split portions of the extension 12 to bind said portions 60 and temporarily lock same against the threads of the screw 24. These niceties of construction permit the crystal to function 65 in a highly satisfactory manner.

I claim:

1. A crystal detector comprising a barrel containing a crystal, an elastic body in the barrel movable with relation to the crystal, and a cat's whisker penetrating the body so that its tip may be exposed therefrom and presented to the crystal, the said body being 100 snugly embraced by the walls of the barrel.

2. A crystal detector comprising a barrel containing a crystal, an elastic body in the 105 barrel movable with relation to the crystal, and a cat's whisker penetrating the body so that its tip may be exposed therefrom and presented to the crystal, the said body being 110 snugly embraced by the walls of the barrel, and means for holding the cat's whisker against longitudinal movement.

FRED J. MARTIN.
